UNITED STATES PATENT OFFICE.

LINUS B. COOLEY, OF MIDDLETOWN, CONNECTICUT.

PUMP.

SPECIFICATION forming part of Letters Patent No. 285,015, dated September 18, 1883.

Application filed November 18, 1882. (No model.)

To all whom it may concern:

Be it known that I, LINUS B. COOLEY, a citizen of the United States, residing at Middletown, in the county of Middlesex and State of Connecticut, have invented certain new and useful Improvements in Pumps; and I do declare the following to be a full, clear, and exact description of the invention, such as will enable others skilled in the art to which it appertains to make and use the same, reference being had to the accompanying drawings, and to the letters and figures of reference marked thereon, which form a part of this specification—

Figure 1 being a side view of my improved pump; Fig. 2, a top view with the cover removed; Fig. 3, a vertical section in the line x , Fig. 1.

Like letters designate corresponding parts in all of the figures.

My improvements have reference to that class of lift-pumps in which the power is given by a crank operated by a handle.

A is the body of the pump, cylindrical in form and of suitable size, which is held in position over the well or cistern by adjusting-bolts $a a a a$, by means of which it can be placed in any position desired. This body A is composed of an outer cylindrical tube, B, into which fits an inner cylindrical tube, C, of smaller diameter. The inner tube, C, in which the piston works, does not reach as high as the outer tube, B. In the upper part of the tube B, above the tube C, fits a movable cylindrical housing-cap, D. The housing-cap is provided with a flange, b, to limit the depth to which it reaches in the tube B. In the housing-cap D is mounted the crank E, and the whole pump is protected by the hinged cover G. The housing-cap D fits somewhat loosely in the tube B, so that it may be readily moved into any desired position to suit the turning of the handle. The tube B is provided with one or more slits, c, and around it, near the top, is placed a band, H, passing nearly around it, and having parallel projecting parts $d d$, through which passes a bolt, e. By means of this bolt the band H is tightened around the tube B, which is thereby contracted sufficiently to hold the housing-cap D firmly in the position desired. The piston I, which is of any ordinary or suitable construction, fits

in the tube C, and is connected with the crank E by means of the double connecting-rod L. To the center of the piston is rigidly attached 55 a vertical rod, M. Between the two parts of the connecting-rod L is located a bar, O. This bar is of a length nearly equal to the inner diameter of the outer tube, B, and its ends rest in the space between the tube C and the movable housing-cap D. This bar at its two ends is enlarged and the ends cut circular, to be adapted to the circular shape of the tube C, which enlargements give broader bearings and firmer support to the ends, prevent lateral displacement, and render any fastening unnecessary. In the center of the bar O is a hole, f, through which the free end of the vertical rod M passes. The rod is of sufficient length, so that there is no danger of its ever slipping out 70 of the hole f. The vertical rod M, passing through the guide-bar O, is compelled thereby to retain its vertical position at every point when the crank is operated, and the piston I, being rigidly connected at right angles to the 75 rod M, also of necessity retains a constant horizontal position in the tube C, and thus the rocking of the piston, which would wear the packing and would render the action of the pump more difficult, is prevented. Below the 80 check-valve P is situated a vent-valve, Q, by which the water may be permitted to run down and freezing prevented. The vent-valve Q being opened and the water in the pipe below the check-valve P having run down, a 85 few turns of the handle of the crank will remove all the water between the piston-valve and the check-valve by raising the check-valve and permitting the water between the piston-valve and the check-valve to run down. 90

What I claim as new, and desire to secure by Letters Patent, is—

1. In a pump, the crank E, mounted in a movable housing-cap, D, substantially as and for the purpose herein specified. 95
2. The movable cap D, carrying the cranks, in combination with a contractile case or cylinder, B, and a tightening-band, H, substantially as and for the purpose herein specified.
3. The combination of the movable guide-bar O and movable crank-carrying cap D with the divided connecting-rod L, striding the guide-bar, substantially as and for the purpose herein specified. 100

4. The combination of the vertical rod M, attached to the piston I, the guide-bar O, and the divided connecting-rod striding the said bar, substantially as and for the purpose herein specified.

5. The vent-valve Q, located below the check-valve P, whereby the water in the pipe below said check-valve is permitted to run down

when said vent-valve is opened, substantially as set forth.

In testimony whereof I affix my signature in presence of two witnesses.

LINUS B. COOLEY.
